SHOE

Filed Sept. 12, 1931

UNITED STATES PATENT OFFICE

GEORGE H. GILLIS, OF FITCHBURG, MASSACHUSETTS

SHOE

Application filed September 12, 1931. Serial No. 562,533.

The invention relates to a shoe the bottom of which includes an outer sole, an inner sole and a shank stiffener interposed between the shanks of the soles the rear end portion of the stiffener being connected with the heel end of the outer sole and the forward end portion with the ball portion of the outer sole.

The ball portion is subjected to much flexure when the wearer of the shoe is walking, so that when the forward end portion is connected as usual by fastening means formed independently of the outer sole and driven into the ball portion thereof, the connection is liable to be disrupted by the flexure, the forward end of the stiffener being thus left in an objectionably loose condition. There is no such liability at the rear end of the stiffener because this end is connected with the inflexible heel portion of the outer sole so that driven fastening means may be unobjectionably employed as the connection between the rear end portion of the stiffener and the heel end of the outer sole.

One object of the invention is to provide a connection between the forward end portion of the stiffener and the ball portion of the outer sole, which is not open to the above mentioned objection. To this end I provide the fore part of the outer sole with an inseparable protuberance on its inner or upper side adjacent the ball line, said protuberance supporting a portion of the inner sole and having a confining abutment bearing on the forward end portion of the shank stiffener and formed to cooperate with driven fastening means constituting the usual connection between the rear end of the stiffener and the heel end of the outer sole, in preventing displacement of the stiffener in any direction, the abutment being inseparable from the outer sole and preventing liability of detachment of the forward end of the stiffener therefrom by flexure of the ball portion of said sole.

Another object is to prevent displacement of said abutment from its predetermined position toward the toe end of the shoe when the outer sole is of an elastic material such as rubber or a composition containing rubber,

the fore part of an elastic outer sole being liable to be stretched and caused to creep forward when the wearer of the shoe is walking. To this end I form the protuberance as a 55 filler of the same material as the sole and adapted to support the entire fore part of the inner sole, which is of relatively inextensible material such as leather, the shoe bottom including rigid fastening means connecting the toe portion of the filler with the toe portion 60 of the inner sole and preventing longitudinal stretching or forward creeping of the outer sole fore part and forward displacement of the abutment which is located at the rear end of the filler.

Of the accompanying drawing forming a 65 part of this specification Figure 1 is a top plan view of the preferred construction of the outer sole, and shows a shank stiffener associated therewith.

Figure 2 is a section on line 2—2 of Figure 1.

Figure 3 is a section on line 3—3 of Figure 1.

Figure 3a is a view similar to Figure 3, 70 showing a different form of the abutment.

Figure 4 is a top plan view of a sole differing from that shown by Figure 1, and a shank stiffener associated therewith.

Figure 5 is a section on line 5—5 of Figure 4.

Figure 6 shows in section portions of a shoe having the outer sole shown by Figure 1.

Figure 7 is an enlargement of a portion of Figure 6.

Figure 8 shows in section portions of a shoe having the outer sole shown by Figure 4.

Figure 9 is an enlargement of a portion of Figure 8.

The same reference characters indicate the 80 same parts in all of the figures.

Referring first to Figures 1, 2, 3 and 6, showing the preferred embodiment of the invention, 12 designates a molded elastic outer sole of rubber, or a composition containing rubber, provided on its inner side of its fore part with an inseparable protuberance of the same material, constituting a 85 filler 13 formed to support the fore part of the insole 14, and occupy the space usually 90 100

occupied by a layer of the usual plastic "bottom filler". The rear end of the protuberance 13 is located adjacent the ball line of the outer sole, and is provided with a recess designated as a whole by 15 in Figures 2, 3 and 3a. Said recess opens toward the heel end of the outer sole and is formed to receive the forward end portion of a shank stiffener 16 when the stiffener is moved forward toward the toe end of the sole.

The recess 15 has walls bearing on both sides and edges, and on the forward end of the stiffener, as shown by Figures 2, 3 and 3a, said walls being adapted to hold the stiffener 15 down on the outer sole, and prevent forward endwise movement of the stiffener and edge-wise movement of its forward end portion in either direction.

The protuberance and its recess are adapted to couple the forward end of the stiffener to the outer sole much more quickly and durably than fastening means such as cement or stitches employed to connect the stiffener with the outer sole.

The rear end of the stiffener 16 is secured to the heel end of the outer sole as by driven fastening means such as the usual center nail 170 (Fig. 6) driven into the shoe heel 18 and rubber heel 19, and engaging the rear end of the stiffener.

It will be seen that the walls of the recess 15 cooperate with the driven fastening means 170 in preventing displacement of the stiffener in any direction, and that the inseparability of the protuberance and its abutment 15 from the outer sole prevents all liability of the detachment of the forward end of the stiffener from the outer sole by flexure of the ball portion thereof.

The shoe bottom formed by the outer sole, filler, and inner sole includes rigid fastening means connecting the toe portion of the filler with the toe portion of the inner sole so that the leather inner sole which is relatively inextensible, prevents longitudinal forward extension or creeping of the outer sole and forward displacement of the abutment 15 from its predetermined position.

The creeping of the outer sole also causes the toe end thereof to protrude forward abnormally from the toe end of the upper 16 which is very objectionable. The rigid fastening means provided for uniting the toe end of the raised portion or filler to the toe end of the inner sole prevents both the forward protrusion of the toe end of the outer sole, and the forward displacement of the abutment 15.

I prefer to embody said rigid fastening means in rigid washers 17 (Fig. 6) embedded in the toe end of the raised portion or filler, and headed nails 18 driven into the outer sole through the washer and into the inner sole, and clinched on the latter. There may be

any desired number of washers 17 and the accompanying nails.

The outer sole 12a shown by Figures 4, 5, 8 and 9 is provided on the inner side of its fore part with a raised protuberance 13a of more limited area than the protuberance 13. In the rear end of the protuberance 13a is formed a recess 15a, adapted to function like the walls of the recess 15. The top surface of the protuberance 15a supports a minor portion of the inner sole fore part and is preferably convex and has a substantially semicircular marginal portion merging into the inner side of the outer sole 12a. If the sole 12a is a part of a welt shoe, a layer 19 of the usual bottom filler may be applied to the inner side of the outer sole fore part in position to support the major portion of the fore part of the inner sole 14 as shown by Figures 8 and 9.

I reserve the right to make the sole and its protuberance of any suitable material not necessarily elastic.

When the outer sole is of molded elastic material the forward end of the stiffener may be molded in the protuberance, the stiffener end shaping the abutment.

The shoe may include the usual welt 20, inseam stitches 21 securing the welt to the upper and inner sole, and outseam stitches 22 securing the welt to the outer sole. When the outer sole 12a is made of molded elastic material its toe portion may be provided with washers 17 engaging the heads of nails 18 driven into the inner sole as shown by Figures 8 and 9.

I claim:

1. An outer sole of elastic material having on its upper side an inseparable protuberance of the same material, formed as a filler having a marginal edge spaced from the margin of the outer sole fore part by a welt seat, the rear end of said filler being provided with a confining abutment formed to bear on the forward end portion of a shank stiffener associated with the shank portion of the sole, the toe end of the filler being provided with rigid washers embedded therein for the purpose specified.

2. A shoe whose bottom includes an outer sole, an inner sole, and a shank stiffener interposed between the shanks of the soles, the rear end of the stiffener being secured by fastening means to the heel end of the outer sole, the outer sole having a confining abutment fixed thereto and formed to contact only with external surface portions of the forward end of the stiffener and cooperate with the rear end fastening means in preventing displacement of the stiffener in any direction, the shoe bottom including also rigid fastening means connecting the toe portion of the outer sole with the toe portion of the inner sole to prevent longitudinal stretching.

of the fore part and forward displacement of the said abutment.

3. A shoe whose bottom includes an outer sole, an inner sole, and a shank stiffener interposed between the shanks of the soles, the rear end of the stiffener being secured by fastening means to the heel end of the outer sole, the fore part of the outer sole having an inseparable protuberance adjacent the ball line, and projecting above its inner side to support a portion of the inner sole fore part, said protuberance having a recess opening toward the heel end and receiving an end portion of the stiffener, the recess having walls bearing on both sides and edges, and on the forward end of the stiffener, so that a stiffener whose opposite end is attached as usual to the heel end of the outer sole, is inseparable at its front end from the ball portion of said sole by flexure of said ball portion.

4. A shoe whose bottom includes an outer sole, an inner sole, and a shank stiffener interposed between the shanks of the soles, the rear end of the stiffener being secured by fastening means to the heel end of the outer sole, the fore part of the outer sole having an inseparable protuberance on its inner side adjacent the ball line, supporting a portion of the inner sole and provided with a confining abutment bearing on the forward end portion of the shank stiffener, and formed to cooperate with the rear end fastening means in preventing displacement of the stiffener in any direction, the abutment being inseparable from the outer sole and preventing liability of detachment of the forward end of the stiffener therefrom by flexure of the ball portion of said sole, the outer sole and its protuberance being of elastic material, the protuberance being formed as a filler having a marginal edge face spaced from the margin of the outer sole fore part by a welt seat, the shoe including a welt and inseam and out-seam fasteners, the inner sole being of practically inextensible material, the shoe bottom including rigid washers embedded in the toe end of the filler and headed nails driven into the outer sole, the washers, the filler, and the toe portion of the inner sole, the nail heads abutting the washers and cooperating therewith and with the inner sole in preventing longitudinal stretching of the outer sole fore part and forward displacement of said abutment.

5. A shoe whose bottom includes an outer sole, an inner sole, and a shank stiffener interposed between the shanks of the soles, the rear end of the stiffener being secured by fastening means to the heel end of the outer sole, the fore part of the outer sole having an inseparable protuberance on its inner side adjacent the ball line, supporting a portion of the inner sole and provided with a confining abutment bearing on the forward end portion of the shank stiffener, and formed to cooperate with the rear end fastening means in preventing displacement of the stiffener in any direction, the abutment being inseparable

from the outer sole and preventing liability of detachment of the forward end of the stiffener therefrom by flexure of the ball portion of said sole, the outer sole and its protuberance being of elastic material, the protuberance being formed as a filler having a marginal edge face spaced from the margin of the outer sole fore part by a welt seat, the shoe including a welt and inseam and out-seam fasteners, the inner sole being of practically inextensible material, the shoe bottom including rigid washers embedded in the toe end of the filler and headed nails driven into the outer sole, the washers, the filler, and the toe portion of the inner sole, the nail heads abutting the washers and cooperating therewith and with the inner sole in preventing longitudinal stretching of the outer sole fore part and forward displacement of said abutment.

6. An outer sole having an inseparable protuberance located on its inner side adjacent the ball line, said protuberance projecting above the sole to support a portion of an inner sole fore part, and having a recess opening toward the heel end and formed to receive an end portion of a stiffener, the walls of said recess being formed to bear on both sides and edges and on the forward end of a stiffener inserted therein.

In testimony whereof I have affixed my signature.

GEORGE H. GILLIS.
